CLAIM

The ornamental design of a padding for a cervical collar, as shown and described.

DESCRIPTION

FIG. 1 is a top, front perspective view of a padding for a cervical collar, showing our new design;

FIG. 2 is a bottom, rear perspective view thereof;

FIG. 3 is top plan view thereof;

FIG. 4 is a left side elevation view thereof;

FIG. 5 is a bottom plan view thereof;

FIG. 6 is a front elevation view thereof;

FIG. 7 is a rear elevation view thereof; and,

FIG. 8 is a top, front perspective view of the padding for a cervical collar of FIG. 1, shown in condition of use for clarity of disclosure.

In the drawings, the broken lines depict environmental subject matter and form no part of the claimed design.
